UNITED STATES PATENT OFFICE.

PIERCE R. McCRARY, OF EAST NORWALK, CONNECTICUT.

APPARATUS FOR ABSTRACTING HEAT FROM FLUIDS.

Application filed May 14, 1919. Serial No. 297,060.

To all whom it may concern:

Be it known that I, PIERCE R. McCRARY, a citizen of the United States, residing at East Norwalk, in the county of Fairfield and State of Connecticut, have invented a new and useful Improvement in Apparatus for Abstracting Heat from Fluids, of which the following is a specification.

This invention relates to apparatus which is adaptable for cooling, liquefying or condensing fluids, and while particularly adapted for refrigerating systems, it is applicable for use in the fractional distillation of gases or in the liquefaction of gases.

The object of the invention is to provide an efficient method and simple apparatus for this purpose, and this object is attained by building a structure which is in the nature of a combined condenser and cooling tower and by means of pumps circulating through this structure vaporized water or other liquid and rarified air or other gases and utilizing the combined and co-operating effect of both liquid and gas to abstract heat units from 25 the fluid to be cooled, liquefied, condensed or otherwise treated.

The apparatus illustrated as embodying this invention has a casing containing coils of pipe through which the fluid to be treated is circulated. Extending through the center of the coils is a stand pipe that is connected with a liquid circulating pump and is provided with adjustable outlets at different heights for throwing upon the coils 35 a fine spray or vapor of the heat absorbing liquid that is circulated by the pump. The casing also has an air or gas inlet near one end and an outlet near the other end that is connected with an air or gas exhaust pump 40 or suction blower which causes a rarification of the air or gas in the casing and produces a rapid circulation therethrough which absorbs and carries away heat directly from the coils and also from the cooling vapor 45 that is sprayed onto the coils.

In the views Fig. 1 shows a central section of the tower casing and condensing coils, with the liquid pump and the gas pump shown in side elevation. Fig. 2 shows a 50 horizontal section taken across the casing on the plane indicated by the dotted line 2—2 on Fig. 1. Fig. 3 shows, on larger scale, a central section through one of the liquid spraying outlets on the stand pipe. Fig. 4 55 shows a central section of a modified form

of liquid spraying outlet that may be utilized.

The base 1 of the casing is desirably a circular casting. Set upon the base with its lower end in a suitably packed groove is 60 a cylindrical shell 2, and placed upon the top of the shell is a cast cap 3 that has a suitably packed groove for receiving the upper end of the shell. These parts are tied together by the stand pipe 4 which has its lower end threaded and screwed into a threaded hub 5 projecting upwardly from the interior of the base, and has its upper end threaded for receiving the nut 6 which screws down upon the cap with sufficient 70 strength to secure the parts tightly. In the casing and located in position before the casing and cap are set in place, are two coils, the smaller coil 7 being located within the larger coil 8. These two coils are joined at 75 the top by a connection 9. The liquid or gas to be cooled, condensed or otherwise treated is circulated in a common manner through these coils, flowing in through the inlet 10 that passes through the base and 80 connects with the bottom of the larger coil, and flowing out through the outlet 11 that passes through the base and is connected with the lower end of the smaller coil.

A liquid pump 12 is connected by an intake pipe 13 with the chamber in the base and is connected by the outflow pipe 14 with a passage 15 in the base that leads to the open lower end of the stand pipe. At various heights on the stand pipe are a number 90 of lateral orifices 16, and fastened on the stand pipe about these openings is a sleeve 17 with openings 18 that register with the openings in the pipe. The upper end of the sleeve is threaded and the lower end is 95 provided with an outwardly extending circular flange or upwardly turned circular spray cup 19. Threaded on the sleeve is a collar with an outwardly extending circular flange or downwardly turned circular 100 spray cup 20. The opposing surfaces 32 and 33 of the sleeve and collar flanges may be made substantially parallel as illustrated in Fig. 4. The orifice 21 between the spray flanges is adjusted to the necessary width to 105 effect the desired result by turning the collar on the threaded sleeve. When the liquid pump is in operation, water or other liquid is forced through the base and up through the stand pipe and thrown out through the 110

orifice between the flanges in a disk-like spray or vapor so as to envelop the coils and absorb heat radiated through them from the fluid that is circulating in them. The sprayed liquid precipitates and collects in the chamber in the base which may at all times contain a quantity of cooling liquid and is returned to the pump and again circulated. Thus the same liquid may be used over and over.

Through the shell near its lower end are openings 22 for the ingress of air or other gas, and movable up and down on the exterior of the shell over these openings is a band 23. By sliding this band up or down the area of the air intake openings may be enlarged or reduced for the purpose of increasing or decreasing the inflow of air, and thus the degree of vacuum or rarification of air in the casing may be regulated as desired.

The intake 24 of an exhaust pump or suction blower 25 is connected by a pipe 26 with the chamber in the cap at the top of the casing and the outlet 27 from this pump may lead to any desired locality. The shaft 28 of the liquid pump and the shaft 29 of the air pump are illustrated as aligned and connected by a coupling 30 so that both

pumps may be driven by a single pulley 31.

When power is applied both pumps are driven rapidly. This causes the liquid pump to draw liquid from the chamber in the base and force it up the stand pipe and out through the circular outlet orifices in disk-like sheets with sufficient velocity to form a fine spray or vapor. The air pump produces a partial vacuum in the casing and air rushes in through the air inlet openings which are restricted so as to result in the required rarification of the air in the casing. This entering air as it expands in the partial vacuum rapidly absorbs heat units from the cooling spray or vapor through which it must pass and reduces the temperature of the liquid so that it acts as

a very efficient cooling agent and can be used over and over again. If the cooling liquid is projected as a vapor, in vaporizing it absorbs considerable heat, and some of the vapor will be carried off with the air, and this also tends to cool the remaining liquid in the casing below atmospheric temperature. By the combined employment and co-action of suitable quantities of rarified air or other gas and vaporized water or other cooling liquid, and drawing the air through the liquid the temperature of the fluid in the coils of this apparatus may be reduced to the degree necessary to effect the desired result on that fluid, such as, condensing it, or liquefying it, or breaking it up.

The invention claimed is:—

1. An apparatus for absorbing heat from fluids which consists of a base, a shell mounted on the base, a cap on the shell, a stand pipe holding said parts together, said shell having adjustable air in-let orifices and said stand pipe having adjustable liquid ejecting orifices, means for forcing liquid into said stand pipe and withdrawing liquid from said base, means for withdrawing air from said shell, and a coil of pipe in said shell and surrounding the stand pipe.

2. An apparatus for absorbing heat from fluids which consists of a base, a shell mounted on the base, a cap on the shell, a stand pipe tying said parts together, said base having a liquid in-let opening communicating with the stand pipe and an outlet opening adjacent thereto, said shell having air inlet orifices through its wall near the lower end, said cap having an outlet opening at one side, and said stand pipe having outlet orifices at various heights and means about said orifices for forming liquid into spray together with fluid conduit means arranged within the shell and surrounding the stand pipe for the purpose specified.

PIERCE R. McCRARY.
